UNITED STATES PATENT OFFICE.

GEORGE W. BRIDGES, OF MINDEN, LOUISIANA.

SAW-ADJUSTING DEVICE.

Application filed June 8, 1927. Serial No. 197,296.

My invention relates to saw adjusting devices, and has particular reference to such a device adapted for use with a two saw one man lumber trimmer, whereby the saws may be moved back and forth in relation to each other by power instead of by hand, as is now customary.

With the above and other objects in view, my invention consists in the combination and arrangement of parts hereinafter described and claimed, it being understood that, within the scope of what is claimed, changes may be made in the precise embodiment shown without departing from the spirit of the invention.

In the drawing:

Figure 1 is a plan view of a portion of a two saw one man lumber trimmer, showing my invention in connection therewith.

Figure 2 is a side view partly in section of a portion of the trimmer showing my invention in connection therewith.

Figure 3 is an end view partly in section and showing the automatic stop.

Figure 4 is a detail of the foot operated bell cranks.

Figure 5 is a detail of the forked lever.

In the use of a two saw one man lumber trimmer the saws are required to be separated in spaced relation to each other, and it is sometimes desirable that the relationship of the saws be varied, for obvious reasons. Ordinarily the variation is accomplished by means of a crank adapted to operate a rack and pinion or screw whereby the saw heads are moved transversely of the table. My invention is designed to render this operation more facile by using power to accomplish the movement of the saw heads, and to place the control for the power elements in a location convenient for the operator so that he will not have to move himself from his customary operating position in order to adjust the spacing of the saw heads.

Referring now more particularly to the drawings, my invention comprises a frame generally indicated by 1, having slidably journaled thereon a transverse shaft 2; a pair of opposing friction bevel wheels 3^a, 3^b are positioned in spaced relation intermediate the said shaft 2; a sprocket wheel 4 is positioned at one end of the said shaft 2; a flanged collar 5 is positioned on the said shaft 2 by means of set collars as at 5^a; a forked lever 6 is adapted to engage the said flanged collar 5; the said lever being posi-

tioned on the vertical shaft 7 journaled in the bracket bearings 8, 8^a affixed to the said frame 1; an operating handle 9 is positioned on the upper end of the said shaft 7, and extends across and over the said frame 1 so as to be adaptable to be manipulated by the operator of the trimmer.

A shaft 10 is journaled right angularly to the said shaft 2 and has positioned on one side thereof a friction bevel pinion 11 adapted to freely rotate intermediate the said bevel wheels 3^a and 3^b, and adapted to be alternately engaged by the said bevel wheels 3^a and 3^b when the said wheels 3^a and 3^b are moved transversely with relation to the said bevel pinion 11 whereby one or the other of the said wheels 3^a and 3^b will come in contact with the said pinion 11. A flanged pulley 12 is mounted intermediate the said shaft 10, and is adapted to be driven from any rotating part of the trimmer 13 as by the belt 14.

The adjusting shaft 15 of the trimmer saw is journaled transversely above the frame 1, a sprocket wheel 17 is positioned on the said shaft 15 in line with the aforesaid sprocket wheel 14; and a sprocket chain 18 is adapted to engage the said sprocket wheels 17 and 4, whereby rotary motion is communicated from the shaft 2 to the shaft 15.

In the operation of the device, when the operator of the trimmer desires to adjust the spacing of the saws, he moves the handle 9 so as to cause the forked lever 6 to engage the flanged collar 5 whereby the said shaft 2 is caused to have a slight transverse movement relative to the frame 1 and the shaft 10 so as to cause one or the other of the said bevel wheels 3^a, 3^b to come into contact and engagement with the said bevel pinion 11 whereby rotary motion is communicated from the said pulley 12 and shaft 10 to the said shaft 2 and thence to the adjusting shafts 15 of the trimmer saws, whereby the said saws are caused to move relative to each other so as to thereby vary the spaced relationship of the said saws.

It is obvious that if the pulley 12 runs constantly in one direction the shaft 2 may be caused to run in opposite directions by moving the said shaft to one side or the other, whereby the wheels 3^a and 3^b are caused to engage opposite sides of the pinion 11.

It is obvious that when the adjustment of the trimmer is accomplished by hand the

adjustment may be made very fine and exact without great difficulty, but when the adjustment is made by power, as by my invention, some means should be provided to ensure the exact adjustment of the saws; I provide such a means in connection with my reversing mechanism, as will now be described:

In the figures, 22 refers to the trimmer sill, 10 23 refers to a splined shaft rotatably positioned longitudinally of the trimmer in spaced relation to the said sill 22; an arm 24 is slidably mounted on the said shaft 23 and adapted to be engaged thereby so that the 15 said arm will rotate with the shaft and will be adapted to move longitudinally thereon. A plate 25 is positioned on the said trimmer sill 22; the said plate 25 has provided therein a plurality of slots 26 adapted 20 to have the said arm 24 releasably positioned therein. The said slots 26 are provided in spaced relation along the said plate 25 such that the slots 26 will engage the said arm 24 at points corresponding to pre- 25 determined settings of the saws; in this manner lumber may be trimmed to predetermined lengths without undergoing the necessity of measuring the distances between the saws directly; in the embodiment shown 30 slots 26 are provided for trimming lumber to 8 feet, 10 feet, 12 feet, etc., lengths. At the end of the shaft 23 is positioned a torsional spring 27 adapted to urge the said shaft to rotate so as to cause the said arm 24 to engage the said slots 26. A crank 28 is positioned at the end of the shaft 23 and a dependent link 29 is pivotably connected to the said crank 28; the lower end of the link 29 carries a transverse pin 30, adapted to 40 slidably engage the vertically extending arcuate slot 31 provided in the foot operated bell crank 32. Under normal conditions, that is to say, when the arm 24 is in engagement with one of the said slots 26, the 45 said pin 30 is adapted to engage the upper end of the said slot 31 so as to thereby support the said bell crank in the position shown in full lines in Figure 3, so that the arms of the bell crank are thus positioned vertically 50 and horizontally. Two bell cranks 32 are provided, one on either side of the said link 29, the slot 31 in each bell crank being engaged by the pin 30.

The aforesaid vertical shaft 7 has positioned thereon a double ended crank 33; the bell cranks 32 are pivotably connected to the opposite end of the crank 33 by means of the links 34.

When it is desired to use the automatic stop, it is obvious that the shaft 7 may be turned to right or left by pressing on one or the other of the said bell cranks 32 whereby the forked lever 6 is caused to engage the bevelled collar 5 thereby operating the friction reversing mechanism in the man-

ner as heretofore described. The bell crank 32 on the right hand side will cause the saw 37 to be adjusted to the right, and the bell crank 32 on the left hand side will cause the saw to be adjusted to the left. A foot pad 70 35 is provided on the said bell cranks 32.

When one of the said cranks 32 have been pressed down in the manner described so as to cause the reversing mechanism to operate, and the saw 37 to be moved thereby, 75 the link 29 engaging the upper end of the slot 31 is pulled downwardly, thereby rotating the shaft 23 and causing the arm 24 to be disengaged from the slot 26 it had previously been resting in; in this manner the 80 arm 24 is adapted to move over the plate 25 the same distance that the saw 37 moves; the movement of the saw is communicated to the slidable arm 24 by means of a slot 36 provided in the saw block 38. The operator 85 will continue to hold down the bell crank until the arm 24 approaches the slot 26 selected, whereupon the operator may release the bell crank, so that the spring 27 may urge the arm 24 into the said slot 26. At the 90 same time the rotation of the shaft 23 will cause the link 29 to move upwardly, thereby rotating the bell crank 32 so as to cause the link 34 to rotate the said shaft 7 to its neutral position, and the reversing mechanism 95 is rendered inoperative. The arcuate slot 31 is provided in the bell crank 32 in order to permit the relative movement of the pin 30 with the bell crank opposite to the one being used.

One of the saws is represented at 37 in the drawing. It is seated upon a head 37^a which is in turn slidably mounted upon a splined shaft 40. A retractile spring 41 is attached at one end to one side of the saw 105 block 38 as shown at 42, while the other end is attached to the end of the frame. This spring thus serves to normally draw and hold the head 37^a towards that end of the frame. A flexible cable 43 is attached at 110 one end to the opposite side of the saw block 38 as shown at 44, while the other end is tied to the shaft 15 as shown at 45, and winds upon or unwinds from that shaft as the same rotates in one direction or the other. 115 Thus rotation of the shaft 15 results in the longitudinal movement of the saw 37 upon the shaft 40. The saw adjusting mechanism just described for controlling the longitudinal movement of the saw 37 upon the shaft 120 40 is conventional for general purposes, and no invention is claimed for the same per se or in combination.

I claim:

1. In combination with a two saw lumber 125 trimmer, comprising a trimmer frame, a frame sill, saw blocks, saws mounted in the said blocks and means for adjusting the spaced relation of the said saws, a releasable lock for the said adjusting means, the said 130

lock comprising a longitudinally disposed plate positioned on the said frame sill; a plurality of slots provided in the said plate; a longitudinally disposed shaft journaled in 5 the said trimmer frame in spaced relation to the said plate; an arm slidably mounted on the said shaft and adapted to engage the said slots, the said arm rotating with the said shaft; foot operated bell cranks pivoted 10 to the said trimmer frame; a vertically extending arcuate slot provided in the said bell crank; a crank provided on the said shaft; a depending link pivoted to the said crank; a pin extending through the said link adapt- 15 ed to engage the said arcuate slots; a slot provided in the said saw block adapted to engage the said arm; and means for communicating the motion of the said bell crank to the said means for adjusting the spaced 20 relation of the said saws.

2. The combination with a two saw lumber trimmer comprising a trimmer frame, a frame sill, saw blocks and saws mounted in the said saw blocks of means for adjusting 25 the spaced relation of the said saws comprising a transverse shaft slidably journaled in the said frame, a pair of opposing friction bevel wheels mounted in spaced relation on the said shaft; a friction bevel pinion jour- 30 naled in the said frame intermediate the said bevel wheels; means for causing the rotation of the said pinion; means for releasably

engaging the said pinion with either one of 35 of the said bevel wheels, whereby the said transverse shaft may be caused to rotate in one direction or the other, the said means comprising a vertical shaft journaled in the said trimmer frame; a collar positioned on the said transverse shaft, a forked lever positioned on the said vertical shaft and adapted 40 to engage the said collar; means for transmitting the rotation of the said transverse shaft to the said saws; in connection with a releaseable lock comprising a longitudinally disposed plate positioned on the said frame 45 sill; a plurality of slots provided in the said plate; a longitudinally disposed shaft journaled in the said trimmer frame in spaced relation to the said plate; an arm slidably mounted on the said shaft and adapted to en- 50 gage the said slots, the said arm rotating with the said shaft; foot operated bell cranks pivoted to the said trimmer frame; a vertically extending arcuate slot provided in the said bell crank; a crank provided on the said 55 shaft; a depending link pivoted to the said crank; a pin extending through the said link adapted to engage the said arcuate slots; a slot provided in the said saw block adapted to engage the said arm; and means for communicating the motion of the said bell cranks to the said vertical shaft.

In testimony whereof I affix my signature.
GEORGE W. BRIDGES.
